Patented Oct. 3, 1899.

F. C. DELLONE,

HYDROCARBON INCANDESCENT LAMP.

(Application filed Jan. 26, 1899.)

(No Model.)

Attest,

Harry C. White
R. White

By

Inventor:

Fred C. Dellone,

Robert Burns

Attorney.

UNITED STATES PATENT OFFICE.

FRED C. DELLONE, OF CHICAGO, ILLINOIS, ASSIGNOR TO JOSEPH E. BOHNER,
OF NEW YORK, N. Y.

HYDROCARBON INCANDESCENT LAMP.

SPECIFICATION forming part of Letters Patent No. 634,482, dated October 3, 1899.

Application filed January 26, 1899. Serial No. 703,483. (No model.)

To all whom it may concern:

Be it known that I, FRED C. DELLONE, a citizen of the United States, residing at Chicago, in the county of Cook and State of Illinois, 5 have invented certain new and useful Improvements in Hydrocarbon Incandescence-Lamps; and I do hereby declare the following to be a full, clear, and exact description of the same, reference being had to the accompanying drawings, forming a part of this specification.

This invention relates to that type of hydrocarbon incandescence-lamps in which the hydrocarbon - vapor generator is heated by 15 the flame of the lamp-burner and in which the vapor from such generator is discharged into the open end of a commingling-tube, which extends to and has communication with the combustion-chamber of the burner 20 to supply the same with a mixture of air and combustible vapor.

The object of the present improvement is to provide a simple, durable, and efficient formation and arrangement of the vapor-generator for such type of lamps and in which 25 the generation of the gas is effected in a very perfect and uniform manner, all as will hereinafter more fully appear, and be more particularly pointed out in the claims. I attain 30 such object by the construction and arrangement of parts illustrated in the accompanying drawings, in which—

Figure 1 is a side elevation of a hydrocarbon incandescence-lamp, illustrating the preferred arrangement of the present improvement 35 in connection with the other usual parts of the lamp; Fig. 2, a longitudinal sectional elevation of the vapor-generator in a detached condition; Figs. 3 and 4, enlarged detail cross-40 sections of the same at lines x x and x' x' , respectively, Fig. 2.

Similar numerals of reference indicate like parts in the several views.

Referring to the drawings, 1 represents the 45 incandescent burner of the type usual to the present class of lamps and commonly known as the "Welsbach" burner.

2 is the commingling tube or conductor, in 50 which the supply of atmospheric air and combustible gas are commingled and supplied to

the burner 1 to effect an incandescence of the mantle thereof in the usual manner.

3 is the elevated supply tank or reservoir, containing the supply of gasoline or other volatile hydrocarbon.

55

4 is the liquid-hydrocarbon-supply pipe, extending from the lower end of the reservoir 3 to the vapor-generator 5.

In the construction shown in the drawings as illustrative of the present invention the 60 lamp is of the hanging type, and in such construction the supply-pipe 4 and the commingling tube or conductor 2 are rigidly secured together, so as to constitute the support for the burner, as usual in such class of lamps, 65 there being no communication, however, between the two tubes.

6 is a needle or other suitable valve controlling communication between the liquid-hydrocarbon - supply pipe 4 and the vapor- 70 generator 5.

The vapor-generator will preferably be of the usual U or return-bend form shown in the drawings, with its upper and longer member 7 screwing into the side of the vertical supply-pipe 4 in line with the controlling-valve 6, while the lower end and shorter member 8 is provided at its free end with a jet or tip 9, that is in line with the open upper end of the commingling tube or conductor 2, as illustrated in Fig. 1.

75

The vapor-generator 5 will usually be arranged in a horizontal plane above the burner 1 in order to utilize the heat therefor in providing a supply of combustible vapor for supporting the combustion of the lamp.

85

In the present improvement the vapor-generator will be provided with a filling of wires 10, arranged within the bore thereof, and in my preferred construction, as shown in Fig. 90 2, the end of such wires next adjacent to the needle or other valve 6 will not extend to the end of the upper member 7 of the vapor-generator, so as to leave at such end a small receiving-chamber 11 at such point, the purpose 95 of which is to afford a limited supply of liquid hydrocarbon for the vapor-generator independent of the direct flow thereof through the needle-valve aforesaid and by this means prevent any fluctuations of the light due to 100

an irregular flow of hydrocarbon through such valve and which is commonly caused by impurities in such liquid partly or wholly clogging the valve for a time.

5. Intermediate of its length the lower member 8 of the vapor-generator is provided with a vapor superheating or firing chamber 12, that is formed by an omission of the wire filling at such point. Said chamber 12 will preferably be arranged in the vapor-generator at the point thereof that is immediately above the burner 1.

To the rear of the outlet jet or tip 9 of the lower member 8 of the vapor-generator is formed a pressure-supply chamber 13 for the combustible gas, the purpose of which is to cause an even and uniform discharge of such gas through the small orifice of the aforesaid outlet jet or tip 9. Such chamber 13 will be 20 of some length, and at its end next adjacent to the tip will be provided with a baffle-plate or disk 14, preferably formed by a spiral-button formation of the end of one of the filling-wires 10, that is extended forward for such purpose, as clearly illustrated in Figs. 2 and 4 of the drawings.

Having thus fully described my said invention, what I claim as new, and desire to secure by Letters Patent, is—

30. 1. In a hydrocarbon incandescence-lamp, the combination with a burner, and a commingling tube or conductor, of a supply-tank, a supply-controlling valve, a vapor-generating tube or chamber, and a filling of wires

arranged in said generating-tube, said wire 35 filling being interspaced intermediate of its length to form a superheating-chamber in the generator-tube at its point of greatest exposure to the heat of the burner, substantially as set forth.

2. In a hydrocarbon incandescence-lamp, 40 the combination with a burner, and a commingling tube or conductor, of a supply-tank, a supply-controlling valve, a vapor-generating tube or chamber, and a filling of wires 45 arranged in said generating-tube, the said generating-tube having an expansion-chamber next adjacent to its outlet end, substantially as set forth.

3. In a hydrocarbon incandescence-lamp, 50 the combination with a burner, and a commingling tube or conductor, of a supply-tank, a supply-controlling valve, a vapor-generating tube or chamber, a filling of wires arranged in said generating-tube, the said generating-tube having an expansion-chamber 55 next adjacent to its outlet end, and a baffle-plate or disk carried by the wire filling and arranged transversely in said chamber to form a contracted annular passage for the 60 gas, substantially as set forth.

In testimony whereof witness my hand this 21st day of January, 1899.

FRED C. DELLONE.

In presence of—

ROBERT BURNS,
HENRY MOE.
